UNITED STATES PATENT OFFICE.

CHARLES H. READ, JR., AND ANDREW M. COYLE, OF WASHINGTON,
DISTRICT OF COLUMBIA.

SPEED-GOVERNOR FOR ELEVATORS.

SPECIFICATION forming part of Letters Patent No. 392,753, dated November 13, 1883.

Application filed January 5, 1883. Serial No. 259,827. (No model.)

To all whom it may concern:

Be it known that we, CHARLES H. READ, Jr., and ANDREW M. COYLE, of Washington, in the District of Columbia, have invented certain Improvements in Speed-Governors for Elevators, of which the following is a specification.

The aim of our invention is to provide a simple, inexpensive, and reliable governor for controlling the speed of elevator cars or cages, and one which may be applied without the necessity of making deep excavations or making attachment directly to the car.

The improvement is intended more particularly for application to that class of domestic elevators in which the car is raised by a counter-weight and depressed by a water load delivered into the receptacle on the car by a flexible pipe, as represented, for example, in Letters Patent of the United States granted to C. H. Read, Jr., No. 348,586, dated September 7, 1882; but the improvement is also to a limited extent applicable to elevators in which the cars are otherwise operated.

In elevators of the Read type, in which the elevation of the car is effected by a constant weight connected therewith and its depression effected by water or other variable load applied to the car, one of the chief dangers not to be found in other elevators resides in the liability of the weight to carry the car upward at a dangerous speed in the event of the load being suddenly diminished—as, for example, by the accidental escape of the water. Our invention has, in fact, as one of its principal improvements the limitation of the speed of the car in an upward direction.

The accompanying drawing represents a sectional elevation through an elevator provided with our improvement.

Referring to the drawing, A represents the elevator-car, constructed and arranged to move vertically in a suitable wellway or guides in an ordinary or suitable manner.

B represents a suspending rope or cable connected to the car and extended thence over a stationary pulley, C, downward beneath a movable pulley, D, and upward to a stationary support, E.

F represents a weight to counterbalance the car, suspended from the axis of pulley D.

The foregoing parts may all be of ordinary construction and arrangement.

In applying our improvement we locate in or adjacent to the wellway in which the car moves, and where possible entirely above the surface of the ground, a vertical tube or stand-pipe, G, the lower end of which is closed. The pipe is located directly beneath the pulley D, and is filled with water, brine, glycerine, or other suitable fluid to a point near its upper end. Within the tube we mount a piston, H, suspended by a rod, I, from the pulley D. This piston, which serves also to partially or, if desired, to wholly counterbalance the car, is made of considerable length and of such size or form as to allow the passage of the fluid wholly around its exterior surface between it and the pipe.

The upper end of the stand-pipe G is attached to or extended upward in the form of an air-chamber, J, the upper end of which is closed by a head or cap, j, which loosely encircles the rod. An air-pipe, K, leads from the upper portion of the air-chamber J downward into the upper end of the stand-pipe at or near the surface of the fluid. A loose diaphragm or piston, M, is located in the air-chamber loosely around the piston-rod, which is provided with a collar, i, adapted to act beneath and lift the piston M when the car is near its lower limit and the piston H near the upper end of the stand-pipe.

The operation of the piston is as follows: As the car ascends and descends its suspending-rope B, acting through the pulley D, raises and lowers the piston-rod and the piston-weight H. During the ascent of the car the weight H descends in the stand-pipe; but, owing to the fact that the annular space around it for the passage of the fluid is of small area, the weight is prevented by the fluid thereunder from descending rapidly, and consequently the sudden elevation of the car is prevented although the weight thereon should from any cause fall considerably below that of the counter-weight. As the car descends the weight H rises in the stand-pipe, being retarded by the weight of the superincumbent fluid, which descends slowly around it. Owing to the fact that the weight of the fluid column above the piston H diminishes as the latter approaches

the top of the stand-pipe, it is found advisable to provide supplemental means for checking the motion of the car at the end of its descent, and it is for this purpose that we employ the 5 air-chamber J and loose piston M. When the car is near the foot of the shaft and the weight H near the top of the stand-pipe, the collar i acts against the piston M and carries the same upward, thereby compressing in the upper end 10 of the air-chamber the contained air, which serves as an elastic cushion. The air escaping through the pipe K and around the piston-rod J allows the piston to rise slowly. By means of the air-cushion thus provided the 15 rapidly-descending car may be arrested quickly and without shock.

The pipe K may be omitted and the air permitted to escape solely around the piston rod or through any other restricted opening provided for the purpose. 20

The counter-weight F may be omitted and the piston-weight H made of suitable size to alone counterbalance the car. 25

It is obvious that instead of permitting the 25 fluid to pass wholly around the exterior surface of the piston-weight the latter may be closely fitted externally to the stand-pipe, but provided with restricted openings for the passage of fluid through it.

30 In order that the speed to which the car is restricted by the governor may be increased or diminished, we propose to provide a supplemental pipe, O, leading from the upper to the lower end of the stand-pipe, and provided 35 with a suitable throttling-valve, P. This pipe forms a supplemental passage for the fluid from one end to the other of the stand-pipe around the piston. If desired, the fluid may pass wholly through this pipe instead of passing 40 partly around or through the piston.

It is to be observed as an important feature of our invention that the stand-pipe and the fluid therein are so combined with the piston-weight as to limit its descent, and thus limit 45 the speed of the ascending car.

We are aware that valve-pistons moving 50 through a fluid column have been combined with a car mechanically lifted to control the speed of its descent, their construction being such that they did not control the speed of its ascent.

Having thus described our invention, what we claim is—

1. In an elevator in which the elevation of the car is effected by a constant counter-weight and its depression effected by the application of a variable load directly thereto, the combination of the car, its suspending-rope, the counter-weight applied to said rope and arranged to effect the elevation of the car, and the stand-pipe supplied with liquid and fitted to the weight to retard the descent of the same, whereby the car is prevented from rising at a dangerous speed in the event of its load being improperly reduced. 55

2. In combination with the elevator-car, its suspending-rope, and a piston-weight suspended by said rope, a stand-pipe in which said weight is loosely fitted, a fluid column in said pipe, an air-chamber at the top of said pipe, and a loose piston mounted in the air-chamber and adapted to be lifted with the piston-weight as the latter completes its ascent. 70

3. An elevator car provided with a water-chamber and a pipe for filling the same to effect the depression of the car, in combination with a counter-weight connected to and adapted unaided to lift the car, a vertical stationary pipe in which the weight rises and falls, and a liquid column in said pipe, the 80 pipe and piston being fitted, as described, to restrict the flow of the fluid past the weight both during its ascent and its descent, whereby the car is prevented from either ascending or descending at an objectionable speed. 85

4. In a speed-governor for elevators, the stand-pipe, the fluid column therein, the air-chamber at its top, the return-pipe K, and the loose piston M, in combination with a piston-weight, H, and its rod adapted to lift the 90 piston M as the weight H completes its ascent.

In testimony whereof we hereunto set our hands, this 24th day of December, 1887, in the presence of two attesting witnesses.

CHARLES H. READ, JR.
ANDREW M. COYLE.
